United States Patent

Des. 239,548

Patented Apr. 13, 1976

239,548

DIAGNOSTIC SLIDE

Robert Schiff, Mission Viejo, and John C. Wilson, Anaheim, Calif., assignors to Baxter Laboratories, Inc., Deerfield, Ill.

Filed Mar. 25, 1974, Ser. No. 454,209

Term of patent 14 years

Int. Cl. D24—02

U.S. Cl. D32—1 R

FIG. 1.

FIG. 4

FIG. 2.

FIG. 3.

FIG. 1 is a perspective view of a diagnostic slide, showing our new design;

FIG. 2 is a side view of the slide taken in the direction of line 2—2 of FIG. 1;

FIG. 3 is an end view thereof taken in the direction of line 3—3 of FIG. 1; and

FIG. 4 is an elevational view as seen from underneath of FIG. 1.

We claim:

The ornamental design for a diagnostic slide, as shown and described.
